[57] CLAIM

The ornamental design for a telephone stand, as shown
and described.

DESCRIPTION

FIG. 1 is a perspective view of a telephone stand, show-
ing my new design;

FIG. 2 is a top plan view thereof, of an enlarged scale;
FIG. 3 is a side elevation thereof, of an enlarged scale,
the opposite side being a mirror image of the side
shown; and

FIG. 4 is a front elevation thereof, of an enlarged scale.
The broken line representing a telephone handset are
shown for illustrative purposes only.

FIG. 1

FIG. 2

FIG. 3

FIG. 4
